UNITED STATES PATENT OFFICE.

FRANK A. BROWNELL, OF ROCHESTER, NEW YORK.

CIRCUIT-CONTROLLING MEANS FOR IGNITION CIRCUITS OF MOTOR VEHICLES.

Application filed July 17, 1924. Serial No. 726,522.

The present invention relates to circuit controlling means for ignition circuits of motor vehicles and an object thereof is to provide in the ignition circuit a switch which under normal running conditions of the motor vehicle would be maintained in its normal position, but which when the motor vehicle shifts upwardly at its forward end above a desirable height will control the circuit to stop the motor. Another object of the invention is to provide a switch part locked in normal position and shifted out of such normal position by a gravity operated element which has a lost motion connection with the switch locking means so that the switch will not be unlocked and shifted from normal position except under extreme undesirable conditions. Still another object of the invention is to provide a switch part controlled by a gravity operated member in such a manner that the switch part is not moved away from normal position except under undesirable conditions. To these and other ends, the invention consists of certain parts and combinations of parts, all of which will be hereinafter described: the novel features being pointed out in the appended claims.

In the drawings:

Fig. 1 is a plan view of the circuit controlling means with the cover plate of the casing removed, the switch being shown in closed position;

Fig. 2 is a vertical section through the casing showing the switch in closed position;

Fig. 3 is a transverse section through the casing; and

Fig. 4 is a detail view showing the gravity operated roller shifted to move the locking device from locking position.

The invention is herein illustrated in connection with a closed circuit ignition system, but it is apparent that the invention is not limited to a closed circuit system. In the illustrated embodiment, 1 indicates the main casting of a casing enclosing all of the operating parts and having a removable cover 2. This cover is secured to the main casting so as to provide a water-proof interior for the casing. Two socket terminals 3 connect with the casing, one having a contact 4 at its inner end and the other having a switch part 5 pivoted thereto at 6. In this instance, the normal position of the switch part is in engagement with the contact 4 thereby maintaining the motor ignition circuit of the motor vehicle closed.

Arranged within the casing is an operating member 7 in the form of a weighted lever pivoted at 8 within the casing near the top of the latter and having a bifurcated portion 9 receiving a projection 10 on the switch lever and providing an operating connection with said lever. This operating member depends from its pivot and has its lower and weighted end widened, the lower end being provided with a large pocket 11, the end walls of which form abutments 12 and 13, one side of the pocket being closed by a wall 14.

Below the lower end of the operating member a channel piece 15 is arranged. This channel piece has one side extending upwardly at an incline to provide an inclined guide having a movable controller 16. This controller is in the form of a weighted roller and operates in the pocket 11 between the abutments 12 and 13. Normally, it lies toward the abutment 13, but, when the vehicle moves upwardly at its forward end above a certain height, the roller moves rearwardly on the incline guide of the channel piece 15 toward the abutment 13, and this roller or controller shifts the weighted portion of the operating member to shift the switch part 15 on its pivot 6 away from normal position, that is, in this instance, from closed position, thus breaking the ignition circuit.

So that the weighted operating member will not shift on every movement of the forward end of the vehicle in an upward direction as in the climbing of hills, a locking means is provided for locking the operating member 7 against movement, this locking means being controlled by the controller 16 during an extreme movement of the controller in the pocket 11 relatively to the operating member 7. The locking means, in this embodiment, comprises a lever or arm 17 pivoted at 18 to the forward end of the channel piece 15 and having between its ends a locking projection 19 which extends upwardly through an opening 20 in the bottom wall of the channel piece to engage with the abutment 14 on the operating member, thereby holding said operating member against movement. The channel also has an opening in its bottom wall in rear of the opening 20 and in the inclined portion through which an inclined controlling portion 22 of the locking lever extends. This inclined controlling portion 22 is so positioned with respect to the locking projection 19 that the controller or roller 16 may move back and forth in

the channel for a limited distance without effecting the movement of the locking means, but upon an extreme rearward movement of the controller 16 due to an extreme upward movement of the forward portion of the vehicle, the roller will move on the inclined portion 22 of the locking lever and thus will press the locking projection 19 out of cooperation with the abutment 12 of the operating member 7, the controller roller 16 thereafter engaging the abutment 13, and this roller together with the weight of the operating member 7 shifts the switch part 5 as hereinbefore mentioned. A spring 23 secured to the underside of the channel piece 15 extends forwardly and engages with the lever 17 near its pivot thus giving the locking lever 17 a normal tendency to lie in locking position. The controlling means is so adjusted that it operates whenever the forward end of the machine rises above a predetermined and undesirable height. When the device is used on a tractor and the forward end of the tractor rises, as occurs in some instances, above an undesirable height so as to operate the circuit controlling means, then the latter may be reset by releasing the clutch and lowering the front end of the tractor by force. This causes the weighted lever and roller to be moved under the action of gravity. However, if the machine is climbing a hill or moving over some obstruction its forward end is lowered very slowly and the operating member may not have sufficient momentum to reset the controller. In some instances, in climbing a hill or going over an obstruction, the machine will stop so that the weighted operating lever cannot reset the controller. In order to reset the controller whenever the weighted operating member cannot be brought into action for effecting this result, a resetting device is employed. This resetting device may comprise a plunger 24 guided in the casing and having one end 45 extending to the exterior of the casing to provide a finger piece. The other end of the plunger cooperates with the operating member 7 adjacent the pivot. A spring 26 surrounds the plunger and engages the fixed part 50 of the casing and the abutment 27 on the plunger. The plunger also carries a packing 28 on the abutment for cooperating with the casing about the opening through which the plunger operates, this packing being employed for preventing the entrance of moisture through the opening about the plunger. This resetting device not only permits the controller to be reset when the weighted operating lever fails to reset the controller, but permits the controller to be closed when climbing hills at a greater inclination to which the roller would be set, this result being obtained by holding a finger upon the plunger until a lower inclination has been reached. Should the forward wheels start

to leave the ground while the plunger is held, pressure on the plunger is released and the controller immediately comes into action to operate the switch part. Of course, the resetting plunger may be controlled in any suitable manner. 70

What I claim as my invention and desire to secure by Letters Patent is:

1. A circuit controlling means comprising a movable switch part, locking means, an operating member for the movable switch part held by the locking means in a normal position to and from which it moves under the action of gravity, and a separate gravity operating member movable into engagement 75 with said locking means to move the latter from locking position.

2. A circuit controlling means comprising a movable switch part, a gravity operated operating member for the switch part, a lock 85 for the operating member, and a gravity operated controller movable into engagement with the lock to shift the latter from locking position.

3. A circuit controlling means comprising 90 a movable switch part, an operating member for the switch part, a lock for the operating member, and a gravity operated controller having a movement relatively to the lock and to the operating member and controlling the movement of both the lock and the operating member. 95

4. A circuit controlling means comprising a movable switch part, an operating member for the switch part having an abutment, a lock for the operating member and a gravity operated controller for effecting the movement of the lock of the operating member to release the latter and then movable into engagement with the abutment of said operating member to effect the shifting of said operating member. 105

5. A circuit controlling means comprising a movable switch part, an operating member for the switch part having two abutments, a gravity operated controller, an inclined way 110 on which the controller moves to cooperate with the two abutments of the operating member, and a lock for the operating member controlled by said controller. 115

6. A circuit controlling means comprising a movable switch part, a lock for holding the switch part in normal position, and a gravity operated roller movable into engagement with the lock to shift the latter in order to release the movable switch part and then into engagement with the movable switch part to move the latter from normal position. 120

7. A circuit controlling means comprising a pivotally mounted switch part, a pivotally mounted lock having a locking portion for holding the switch part against movement and also having a controlling portion, and a gravity operated member normally lying 125 out of engagement with the controlling por- 130

tion of the lock and movable into connection with said controlling portion to move the locking portion out of locking position.

8. A circuit controlling means comprising a movable switch part, a pivotally mounted lock having a locking projection for holding the switch against movement and having also a controlling portion, an inclined way having two openings, one through which the locking projection operates and the other through which the controlling portion operates, and a roller movable on the way to cooperate with said controlling portion to move the locking projection in order to release the switch part.

9. A circuit controlling means comprising a movable switch part, a pivoted operating member having a weighted portion provided with a pocket formed with two abutments, a pivotally mounted lock having a locking projection and a controlling portion, the locking projection cooperating with the pivotally mounted operating member, an inclined way provided with two openings in its bottom, one through which the locking projection operates and the other through which the controlling portion of the lock operates, and a roller weight movable on the way and oper-

ating in the pocket of the operating member, said movable roller cooperating with the controlling portion of the locking lever to release the operating member so that the roller with the weighted operating member will move the switch part away from normal position.

10. A circuit controlling means comprising a movable switch part, a gravity operated operating member for the switch part movable by gravity toward and from a locking position, a locking means for holding the gravity operated operating member in locking position, a gravity operated controller for the locking means normally lying out of connection with the locking means, and means for resetting the switch independently of said gravity operated controller.

11. A circuit controlling means comprising a pivotally movable switch part, a pivoted weighted operating member for the switch part, a lock for said operating member, a gravity operated controller for the lock, and means cooperating with said weighted operating member for resetting the switch independently of the controller.

FRANK A. BROWNELL.
